PNEUMATIC THREAD EXTRACTOR FOR
LOOMS

Richard G. Turner, Worcester, Mass., assignor to
Crompton & Knowles Loom Works, Worcester,
Mass., a corporation of Massachusetts

Application April 18, 1938, Serial No. 202,694

14 Claims. (Cl. 139—256)

This invention relates to improvements in thread control mechanisms for automatic looms and it is the general object of the invention to provide pneumatic means for removing the thread extending from the selvage to the outgoing bobbin on transferring beats of the loom.

At the time of transfer in bobbin changing looms a thread extends from the selvage into the shuttle box and along the front wall of the shuttle 10 to and through the shuttle eye, whence it passes to the bobbin. It is desirable to remove this thread so that it may not be whipped into the shed to cause imperfect cloth. It is an important object of my present invention to provide pneumatic means for sucking this thread out of the path of the shuttle together with a presenter to place the thread into the draft of air.

Picking ordinarily occurs when the lay has reached midposition during its backward stroke, and as the shuttle emerges from the box the filling is slackened due to the fact that the shuttle eye is moving toward the selvage. It is another object of my present invention to provide a stationary pneumatic thread extractor operating 25 with a thread controller, such as a hook, which will move to a position behind the filling on transferring beats of the loom and be drawn forwardly to place the filling in a draft of air prior to picking. The result of this relationship is to require 30 the filling to be subjected to a pneumatic force throughout the picking operation.

In one form of my invention the thread controller is a hook normally located within a pneumatic tube and projected from the latter at the 35 time of transfer to a position behind the thread so that subsequent return of the hook will draw the thread into the tube and rearward motion of the lay will not move the thread away from the draft of air. When the hook is mounted in the tube its bight is moved far enough in advance of the rear end of the tube to produce a perceptible bend in the thread which will prevent unhooking when thread slackness occurs due to picking.

It is a further object of my invention to provide a thread accumulator for the primary purpose of preventing loose ends from flying into the path of the shuttle, but I also locate the accumulator near enough to the intake end of the pneumatic system so that the thread extending from 50 the shuttle box can be drawn into the accumulator and become entangled with a mass of threads which serves as a holder to prevent egress of the thread into the path of the shuttle.

One of the advantages of my present invention 55 resides in the fact that the pneumatic system is

substantially stationary on the loom and preferably in front of the lay, the thread controller being used to move the thread into the zone of influence of air rushing into the intake mouth of the pneumatic system. I am not necessarily limited to a hook mounted within the tube, since it is possible to operate the mechanism with one or two hooks located at the side of the tube and acting to move the thread into the draft of air.

With these and other objects in view which will appear as the description proceeds, my invention resides in the combination and arrangement of parts hereinafter described and set forth.

In the accompanying drawing, wherein three forms of the invention are shown,

Fig. 1 is a plan view of the forward part of one end of the lay having the preferred form of my invention applied thereto,

Fig. 2 is an end elevation of a portion of the structure shown in Fig. 1,

Fig. 3 is a detailed vertical section on line 3—3 of Fig. 1 illustrating the relation which the accumulator sustains to the pneumatic system,

Fig. 4 is an enlarged vertical section on line 4—4 of Fig. 1 showing the thread controlled hook 25 projected on a transferring beat of the loom,

Fig. 5 is an enlarged transverse section on line 5—5 of Fig. 4,

Figs. 6 and 7 are diagrammatic plan views showing two modifications of the invention, and 30

Fig. 8 is a detail horizontal section on line 8—8, Fig. 4.

Referring to Figs. 1 and 2, I have shown a loom frame 10 having a breast beam 11, lay 12, top or crank shaft 13 having one revolution for 35 each beat of the loom, and a connector 14 by which the shaft reciprocates the lay. A temple 15 has a thread cutter 16 set in the usual way to sever the weft W from the selvage several picks after transfer. The weft extends from the temple 40 into a shuttle box B containing the depleted shuttle S and lies between the front of the shuttle and a binder 17. The usual picker 18 is actuated when the lay is about midway in its rearward stroke. At the time of picking the weft W extends to the right and rearwardly along a diagonal line from the selvage. As the shuttle moves out of the box toward the selvage the thread W, which may previously have been substantially taut, becomes slackened and unless it is removed 50 from the path of the shuttle will be whipped into the shed defined by the warp threads 20.

The weft replenishing features include a magazine M having two bobbin guideways 25 and 26, respectively, moving about a fixed pivot 27 sup-

ported on a stand 28 carried by the loom frame. A transerrer arm 29 is pivoted on the stand as at 30 and is connected to a latch 31 adapted for engagement with a bunter 32 on the lay. When 5 replenishment is called by mechanism not shown but well understood the latch will be in the full line position shown in Fig. 2 where it will be engaged by the bunter as the lay moves forwardly, the transerrer arm being thereby depressed to 10 the dotted line position in Fig. 2 for the insertion of a fresh bobbin into the shuttle S. The magazine M is shown merely for illustrative purposes and is one of several mechanisms for supplying reserve bobbins which are well-known and can 15 be used with my invention. For further details of the magazine and the manner in which it is controlled reference may be had to my copending application Serial No. 129,245.

A thread cutter 40 is mounted at the rear end 20 of a rod 41 carried by a lever 42 swinging about a fixed pivot 43. The left end of lever 42 is adapted for engagement with some part of the transfer mechanism, such for instance as the depending arm 44. A spring 45 tends normally 25 to move the cutter 40 rearwardly against the front wall of the shuttle but is restrained from doing so by engagement between arm 44 and the left part of lever 42. As the transerrer arm descends, however, arm 44 moves forwardly and 30 spring 45 is free to move the cutter 40 against the front wall of the shuttle to cut the thread at a point closely adjacent to the eye E of the shuttle. After transfer therefore the thread W is severed from the bobbin 46 but is still connected to the selvage, and is held between the binder and shuttle. The cutter of itself forms no part of my present invention and may be substantially the same as set forth in Payne Patent No. 1,881,924.

40 In order to provide pneumatic pressure for the system to be described hereinafter I mount a cylinder 50 in a stand 51 carried by the loom-side and provide said cylinder with a piston 52 having a rearwardly extending piston rod 53 connected to the upper end of a rocking lever 54. The latter is connected by link 55 to the lay as at 56 so that rearward motion of the lay tends to induce a vacuum in the front part of the cylinder and in front of the piston. A flexible 50 tube 57 is pneumatically connected to the interior of the cylinder and extends forwardly. The effect of the reciprocation of the lay is to create a partial vacuum in the tube 57 throughout each rearward motion of the lay, the vacuum continuing during picking. Reference may be had to my co-pending application Serial No. 166,571 for further details of the pump.

The matter thus far described may be of the usual construction and made in accordance with 60 the previously mentioned patents and application. It is deemed sufficient for purposes of the present description to state that on transferring beats of the loom the transerrer arm 29 will descend when the lay is on front center position with the weft W extending from the 65 selvage into the shuttle box B and connected to the bobbin within the shuttle. Descent of the transerrer arm results in severance of the thread W by cutter 40 at a point near the shuttle eye, and on the ensuing back stroke of the lay the shuttle will be picked out of the box to slacken the weft W and at the same time a partial vacuum will be induced in the tube 57.

In carrying my present invention into effect I 75 provide means for removing the weft W from

the path of the shuttle by means including a pneumatic system and a thread presenter to move the thread into the zone of influence of the pneumatic system. Referring to Figs. 2 and 4 I mount a stand 60 on the breast beam and provide the same with a rearwardly extending tube 61 which may be inclined downwardly as suggested in Fig. 4. This tube extends to a point slightly in advance of the reed R of the lay when the latter is forward. The tube fits closely into a bore 62 of the stand and communicates with passage 63 which leads to the base of and communicates with the interior of a thread accumulator 64 mounted on the stand 60. The tube 67 enters the upper part of the accumulator 64 and tends to create a partial vacuum in the accumulator during the backward stroke of the lay. The result of this connection is that during rearward motion of the lay there is an inrush of air into tube 61 and along passage 63 to the interior of the accumulator 64. A screen 65 may be used to prevent passage of threads from the accumulator to the tube 67.

Tube 61 is ordinarily fixed with respect to the breast beam 11 and as the lay moves rearwardly the thread W tends to recede from the intake end of the tube 61. If the tension on the thread W is considerable it may move out of the zone of influence of the air rushing into the metallic tube 61 before the shuttle is picked 30 and it is to prevent this condition that I employ some form of thread presenter for the purpose of moving the thread forwardly or toward the mouth of tube 61. Three mechanisms for accomplishing this result are set forth herein.

In order to provide actuating mechanism for the presenter I employ the mechanism shown in Figs. 1 and 2 where the transerrer arm is shown as provided with an auxiliary arm 70 pivoted as at 71 to a downwardly and forwardly extending rod 72 the lower end of which is pivoted as at 73 to an arm 74 fastened to a shaft 75. The latter rotates in bearings 76 and 77 on the front part of the breast beam 11 and the inner or left end thereof as viewed in Fig. 1 is provided with an upright arm 78. Under normal conditions, with the transerrer arm raised, these parts are in such a position as to locate the arm 78 forwardly, but at the time of transfer the rod 72 is raised to rock shaft 75 in a clockwise direction as viewed in Fig. 2, thereby causing arm 78 to move rearwardly or toward the lay. This actuating mechanism may be used for any of the forms of presenters which I will now describe.

In the preferred form arm 78 is pivoted as at 80 to a rearwardly extending rod 81 sliding through a bore 82 in the base 60 and extending under the tube 61. The rear end of rod 81 is curved upwardly as at 83 and passes through a short slot 84 extending longitudinally forwardly on the underside of tube 61. The bent end 83 extends into the tube and is secured to a shoe 85 having a convex face 86 sliding along the concave interior walls of the tube 61 to close the slot and prevent air leakage through it. Secured to the shoe is a hook 87 which projects rearwardly and has a head 88 so constructed as to define a forwardly and upwardly opening bight for the reception of the thread W. The lay may be slotted as at 90 to receive the head 88, rod 81 and if desired the lower rear part of tube 61.

Under normal conditions the arm 78 is forward, thereby placing the head 88 within the tube 61.

with the bight located entirely forwardly of the intake rear end of the metal tube 61. When the arm 78 rocks rearwardly at transfer the head will be projected into the position shown in full lines 5 in Fig. 4, the rear upper part of the head being inclined as suggested in the drawing so that the hook passes under the thread W and the latter lies in front of the head 88 where it can pass into the bight of the hook. At this time the head of 10 the hook is located behind the reed R to give assurance that the weft W will lie in front of it. This relation occurs when the lay is in forward position and on transferring beats of the loom, the transference arm being down to effect the insertion of the fresh bobbin into the shuttle and 15 also move the hook as described. The cutter 40 severs the thread as this time at a point near the shuttle eye.

When transfer is complete and the lay starts its 20 rearward motion the transfer arm will be raised by well-known mechanism not described with an attendant rocking of shaft 75 in a counter-clockwise direction as viewed in Fig. 2, thereby retracting the head 88 and moving the same into 25 the tube 61. The thread now is disposed as shown in Fig. 8 in engagement with the hook and opposite sides of the tube 61. The retraction of the head 88 is completed some little time before the lay reaches picking position.

30 During continued rearward motion of the lay the shuttle is picked and the weft thread W thereby slackened, but because of the fact that the thread extends into the tube 61 and around the head 88 it is held against unhooking even 35 though it be slack. At this time the pump is creating a vacuum in the tube 61 tending to draw the thread toward the accumulator 64 and as soon as the shuttle is completely out of the box the thread will no longer be bound between the 40 shuttle and the binder 17 and will be drawn into the accumulator. At a subsequent pick the temple cutter 16 will sever the thread at the selvage during a forward beat of the lay and in the immediately ensuing rearward motion of the lay 45 the pump will act to draw the remainder of the thread into the accumulator.

Repeated operations as just described will result in the accumulation of a number of weft threads in the cylinder 64 and the resulting mass 50 of threads T is able to serve by their entanglement with threads freshly drawn into the tube 61 as a thread holder because of the fact that the distance from the intake end of tube 61 to the interior of the accumulator is considerably less 55 than the length of thread extending from the tube 61 to the eye of the shuttle. The draft of air through the accumulator is up and incoming threads are therefore drawn partly into the mass of thread T within the accumulator. This is of 60 particular advantage during forward motion of the lay when the vacuum is temporarily interrupted.

In the first modification of the thread presenter, such as that set forth in Fig. 6, a hook 90 65 similar in many respects to the hook of the preferred form is located outside the tube and has a stem 91 which slides through a bore in the base 60. This hook 90 is on that side of the tube 61 opposite the selvage but it is operated by the 70 mechanism described in connection with Fig. 2 and moves rearwardly during transfer and is then brought forwardly as the transference arm rises to place the thread W across the intake mouth of tube 61. At the subsequent pick the hook holds 75 the thread in the draft of inrushing air and the

vacuum sucks the thread into the accumulator as in the preferred form.

In Fig. 7 I show two hooks similar to the hook 90, these hooks being designated at 95, one hook being to the right and the other to the left of 5 tube 61. These hooks 95 operate in the same way as does hook 90 except that they exercise a tighter control over the weft thread and the bend in the latter tending to prevent unhooking is caused by two hooks outside the tube which, however, act much in the same way as does the single hook as suggested in Fig. 8. The single hook 90 and the double hooks 95 are operated by the arm 78.

From the foregoing it will be seen that I have 15 provided means for presenting the weft thread of an outgoing bobbin to the intake end of a pneumatic thread extracting system, this operation taking place preferably before picking. It will further be seen that in the preferred form the 20 hook is mounted inside the tube 61 so that retraction of the hook draws the thread positively into the tube while it is still held sufficiently taut by pressure between the shuttle and binder 17 to insure definite control of the thread by the 25 hook. The shoe 85 serves to close the slot 84 and prevent leakage of air through said slot. The hook in all of its forms is moved to a point behind the thread and is able by reason of this fact to advance the thread to a position where it is 30 within the zone of influence of the draft of air. Backward motion of the lay, therefore, cannot draw the thread away from tube 61. Furthermore, it will be seen that the accumulator 64 contains a mass of thread T which is able to 35 serve as a thread holder of the ends W because of the close proximity of the accumulator to the tube 61. It will further be seen that the presenting hooks may be located either inside or outside the tube 61 and that whatever the form of the 40 hook it is controlled by the transfer mechanism.

Having thus described my invention it will be seen that changes and modifications may be made therein by those skilled in the art without departing from the spirit and scope of the invention and 45 I do not wish to be limited to the details herein disclosed, but what I claim is:

1. In a weft replenishing loom having a lay and a thread extending from the cloth selvage into a shuttle box on the lay, a pneumatic thread 50 extractor having an intake in front of the thread, means to induce a draft of air into said intake in a direction away from the lay, and means movable from a point behind the thread and intake to engage and move said thread toward the intake.

2. In a weft replenishing loom having a lay and shuttle box into which a thread extends from the cloth selvage, transfer mechanism to insert a reserve bobbin into the shuttle box, a pneumatic 60 thread extractor having an intake mouth in front of the thread, a hook normally in forward position in front of the thread, and means connecting the hook to the transfer mechanism and operative during a transferring operation of the loom 65 to move the hook to a position behind the thread and thereafter move the hook forwardly in engagement with the thread to move the latter toward the intake mouth of the thread extractor.

3. In a weft replenishing loom having a lay and 70 shuttle box into which a thread extends from the cloth selvage, transfer mechanism to insert a reserve bobbin into the shuttle box, a pneumatic thread extractor having an intake mouth in front of the thread, means to induce a draft of air into 75

- said mouth forwardly from the lay, thread control means connected to the transfer mechanism and movable by the latter to a position behind the thread and intake mouth during insertion of the reserve bobbin into the shuttle box, said transfer mechanism operative thereafter to move the thread control means forwardly to engage the rear of the thread and move the same toward the intake mouth of the thread extractor.
10. 4. In a weft replenishing loom having a lay and shuttle box from which a thread extends to the selvage, a pneumatic tube extending transversely from the thread and having an intake mouth adjacent to the thread, means to induce a draft of air into said intake mouth in a direction away from the thread, a thread presenter having a bight to receive the thread, and means to move the presenter while in engagement with the thread into the tube to place the bight within the intake mouth.
15. 5. In a weft replenishing loom having a lay and shuttle box into which a thread extends from the cloth selvage, a pneumatic tube extending forwardly from a point in front of the thread, means to induce a draft forwardly in said tube, and means located within the tube operating independently of the draft of air to move the thread forwardly into said tube.
20. 6. In a weft replenishing loom having a lay and shuttle box into which a thread extends from the cloth selvage, a pneumatic tube extending forwardly from a point in front of the thread, means to induce a draft of air into said tube in a direction forwardly from the thread, a thread hook movable within the tube, and means to move the hook first to a position behind the thread and thereafter move the hook to a position inside the tube to draw the thread into the tube and within the range of action of said draft of air.
25. 7. In a weft replenishing loom having a lay and shuttle box into which a thread extends from the cloth selvage, a tube extending forwardly from the thread and having an intake end in front of the thread, means to induce a draft of air into the intake end forwardly through said tube, a thread hook at one side of the tube, and means to move the thread hook forwardly from a position behind the thread to advance the latter toward the intake opening.
30. 8. In a weft replenishing loom having a lay and shuttle box into which a thread extends from the cloth selvage, a pneumatic tube extending forwardly from the thread and having an intake opening in front of the thread, a thread hook located at each side of the tube, and means to move said hooks forwardly from a position behind the thread and cause said hooks to move the thread toward the intake opening.
35. 9. In a weft replenishing loom having a lay and shuttle box into which a thread extends from the cloth selvage, means to cut the thread at a point adjacent the shuttle eye, a pneumatic thread extractor having an intake mouth adjacent the selvage, means to induce a draft of air into said intake to draw the thread into the extractor while said thread is attached to the selvage, and a thread accumulator communicating with the extractor and having a mass of thread therein located nearer the intake mouth than said means to cut the thread, said mass of thread to have entangling engagement with said thread and hold the same.
40. 10. In a weft replenishing loom having a thread extending from the selvage into a shuttle box, a hollow thread accumulator having a mass of threads therein, a pneumatic thread extractor having an intake mouth communicating with the interior of the accumulator, means to induce a draft of air into the mouth and toward the accumulator, and means to sever the thread at a point farther removed from the intake mouth than the distance from the mouth to the interior of the accumulator, the draft of air thereafter moving the thread into the accumulator and entangling it with said mass of threads.
45. 11. In a weft replenishing loom having a lay and a shuttle at one end thereof with a weft thread extending to the selvage, a hollow thread accumulator having a mass of threads therein, a hollow thread extractor communicating with the interior of the accumulator and having an intake adjacent the thread, means to sever the thread from the shuttle at a point farther from the intake than the accumulator is from said intake, a selvage cutter to cut the thread near the selvage, and means to induce a draft of air into the extractor and accumulator to draw the thread into said accumulator and entangle the same with the mass of threads prior to operation of the selvage cutter.
50. 12. In a weft replenishing loom having a lay and a shuttle at one end thereof with a weft thread extending to the selvage, a hollow thread accumulator, a tubular pneumatic thread extractor communicating with the interior of the accumulator and having an intake mouth adjacent the selvage, a mass of threads in the accumulator above the point of communication between the pneumatic tube and the interior of the accumulator, and means to create a partial vacuum within the accumulator above the mass of threads, the partial vacuum causing a draft of air to enter the mouth and draw the thread therein and into the accumulator and upwardly against the mass of threads to effect entanglement between the thread and said mass of threads.
55. 13. In a weft replenishing loom having a lay and shuttle box from which a thread extends to the selvage, a pneumatic thread extractor tube extending in a direction transverse of the thread and having an intake mouth adjacent to said thread, a thread presenter located on that side of the thread opposite the intake mouth, means to move said presenter while in engagement with the thread toward the intake mouth, and means to induce a draft of air into the intake mouth in a direction from the thread toward said mouth to draw the thread into said tube.
60. 14. In a weft replenishing loom having a lay and shuttle box into which a thread extends from the cloth selvage, transfer mechanism to move a reserve bobbin into the shuttle box, a pneumatic tube stationarily mounted with respect to the loom and extending forwardly from the thread, said tube having an intake opening at the rear end thereof in front of the thread, means to induce a draft of air into the intake opening and through the tube in a direction away from the lay, and means movable from a point behind the intake by the transfer mechanism to engage and move the thread toward said intake opening.
